UNITED STATES PATENT OFFICE.

JOHAN M. ANDERSEN, OF BOSTON, MASSACHUSETTS, ASSIGNOR OF ONE-HALF
TO ALBERT ANDERSON, OF SAME PLACE.

TROLLEY-WIRE CLIP.

SPECIFICATION forming part of Letters Patent No. 532,133, dated January 8, 1895.

Application filed July 9, 1894. Serial No. 516,890. (No model.)

To all whom it may concern:

Be it known that I, JOHAN M. ANDERSEN, residing in Boston, in the county of Suffolk and State of Massachusetts, have invented an

5 Improvement in Trolley-Wire Clips, of which the following description, in connection with the accompanying drawings, is a specification, like letters on the drawings representing like parts.

10 This invention relates to a novel support or hanger for the trolley wire of electric railways, and has for its object to provide a simple, cheap, and efficient device for the purpose specified.

15 In accordance with this invention, the hanger comprises essentially an "ear," adapted to be secured to an insulator or other form of support, such as now commonly employed, and provided on its under side or bottom with 20 preferably two spring or adjustable arms, preferably integral with the body of the "ear." The spring arms referred to, are preferably made concaved or substantially semi-circular on their under surface to substantially conform to the rounded upper surface of the trolley wire, with which they are designed to engage by means of adjusting devices, preferably threaded bolts inserted down through suitable threaded openings in the "ear" and 25 adapted to engage the upper surface of the said spring arms. The "ear" has secured to it a substantially U-shaped metal clip upon which the trolley wire rests, and against the bottom of which the said trolley wire is 30 pressed by the adjustable arms of the "ear." These and other features of this invention will be pointed out in the claims at the end of 35 this specification.

Figure 1 is a side elevation of a trolley wire 40 hanger embodying this invention, a portion of the trolley wire being shown as secured to the said hanger. Fig. 2 is a side elevation of the "ear" with the sheet metal clip, shown in section; Fig. 3, a section of Fig. 1 on the line 45 3-3 looking toward the left, the adjusting bolt being shown in elevation, and Fig. 4, a modification to be referred to.

Referring to Fig. 2, A represents the "ear" of the trolley wire hanger, which may be made 50 of any desired or suitable metal and of any desired or suitable shape, but preferably of

the form herein shown. The "ear" A, in accordance with this invention, is provided on its under side with one or more adjustable or movable arms a, preferably two such arms 55 being attached to or forming part of the central or body portion a' of the "ear" on its under side and extended toward the opposite ends of the said "ear." In the present instance, the arms a are shown as integral with the body portion a' of the "ear" and separated therefrom by spaces a⁴, extended from near the longitudinal center to the opposite ends of the said "ear." The arms a are preferably made concaved or substantially semi-circular on their under side to fit over and embrace the upper part of the trolley wire b, when the said arms are in their adjusted position. 65

The trolley wire b is designed to rest upon 70 the bottom of a substantially U-shaped clip b' of sheet metal or other suitable metal, which may be secured to the ear A in any suitable manner, but I prefer to secure the said clip by providing the "ear" on its opposite sides with hooks, projections or fingers b² adapted to be engaged by the upper edge or wall of slots or openings b³ in the upright sides b⁴ of the said clip. 75

The clip b' may be secured to the "ear" A 80 and the trolley wire b may be passed through the groove formed by the bottom of the clip and the arms a, and the said wire may then be firmly clamped to the hanger by bringing the arms a down in contact with the upper 85 surface of the said wire, with sufficient pressure to force the wire against the bottom of the clip. This movement or adjustment of the arms a may be effected by means of adjusting devices, preferably threaded bolts c 90 extended down through threaded sockets in the ends of the body portion of the "ear," but I do not desire to limit my invention to this particular form of adjusting device, as it is manifest that keys or bars might be driven 95 into the spaces a⁴ and thus force the arms down upon the trolley wire after the manner shown in Fig. 4, wherein h represents the key or bar inserted into the space a⁴ and provided with an upright arm h', having a hole in it 100 through which a threaded bolt h² is extended into a threaded socket in the end of the "ear"

A. In the present instance, the "ear" A is represented as provided with a substantially central boss or enlargement c^4 which is provided with a threaded socket for the reception of the threaded end of a metal stud or shank c^5 , which may be secured to or form part of a suitable insulator not shown, but if desired the said stud may be made integral with the "ear," the said stud being represented as covered by insulating material c^6 .

I claim—

1. In a trolley wire hanger, the combination with an "ear," and a clip secured thereto for the reception of the trolley wire, of an arm secured to said "ear" and adapted to engage the said trolley wire, and means to engage the said arm with said wire, substantially as described.

2. In a trolley wire hanger, the combination with an "ear" provided on its under side with arms extended in the direction of the length of the "ear," and a clip secured to the said "ear" to form a groove for the reception of the trolley wire, of devices to act on said arms to engage them with the trolley wire, for the purpose specified.

3. In a trolley wire hanger, the combination with an "ear" provided on its under side with arms extended in the direction of the length of the "ear" and having concaved under, surfaces, and a clip secured to the said "ear" to form a groove for the reception of the trolley wire, of devices to act on said arms to engage them with the trolley wire, for the purpose specified.

4. In a trolley wire hanger, the combination with an "ear" provided on its under side with arms integral with the said "ear" and extended from the central portion toward the opposite ends of the said ear, a substantially U-shaped clip secured to the sides of the said "ear" and threaded adjusting bolts carried by the "ear" and acting on the said arms to force the trolley wire against the said clip, substantially as described.

In testimony whereof I have signed my name to this specification in the presence of two subscribing witnesses.

JOHAN M. ANDERSEN.
